[57] CLAIM

The ornamental design for a gas-lighter, as shown and described.

DESCRIPTION

FIG. 1 is a perspective view of the gas-lighter showing my new design;

FIG. 2 is a side elevational view thereof on an enlarged scale, the opposite side being a mirror image;

FIG. 3 is a front elevational view thereof on an enlarged scale; and

FIG. 4 is a top plan view thereof on an enlarged scale.
